(57) **CLAIM**

The ornamental design for a multimode sensor, as shown and described.

DESCRIPTION

FIG. 1 is an upper perspective view of a first embodiment of the sensor, the following FIGS. 2-7 also describing the first embodiment;

FIG. 2 is a lower perspective view of the sensor;

FIG. 3 is a front view of the sensor;

FIG. 4 is a left side view of the sensor, the right side view being a mirror image thereof;

FIG. 5 is a rear view of the sensor;

FIG. 6 is a top plan view of the sensor; and

FIG. 7 is a bottom plan view of the sensor.

FIG. 8 is an upper perspective view of a second embodiment of the sensor, the following FIGS. 9-14 also describing the second embodiment;

FIG. 9 is a lower perspective view of the sensor;

FIG. 10 is a front view of the sensor;

FIG. 11 is a left side view of the sensor, the right side view being a mirror image thereof;

FIG. 12 is a rear view of the sensor;

FIG. 13 is a top plan view of the sensor; and,

FIG. 14 is a bottom plan view of the sensor.

The broken lines on the drawings depict portions of the sensor that form no part of the claimed design.
